W. P. GATCHELL,
ATTACHMENT FOR INTERNAL COMBUSTION ENGINES.
APPLICATION FILED JULY 29, 1918.

1,326,044.

Patented Dec. 23, 1919.

UNITED STATES PATENT OFFICE.

WILLIAM P. GATCHELL, OF WINSTED, MINNESOTA.

ATTACHMENT FOR INTERNAL-COMBUSTION ENGINES.

1,326,044.

Specification of Letters Patent. Patented Dec. 23, 1919.

Application filed July 29, 1918. Serial No. 247,178.

To all whom it may concern:

Be it known that I, WILLIAM P. GATCHELL, a citizen of the United States, residing at Winsted, in the county of McCloud and State of Minnesota, have invented certain new and useful Improvements in Attachments for Internal-Combustion Engines, of which the following is a specification.

This invention relates to attachments for automobile motors and has particular reference to the well-known Ford motor, forming part of the well-known Ford automobiles.

An object of the invention is to provide extension means whereby the timer mechanism on the Ford motor may be moved from its present location to the opposite side of the crank shaft and located in the upper portion of the interior of the hood.

A further object of the invention is to provide a device adapted to fit into the recess provided for the present Ford timer, (which latter is mounted on the cam shaft) and to extend therefrom upwardly and outwardly away from the exhaust manifold.

Other objects will be pointed out as they appear in the specification.

The invention consists in the construction, combination, and arrangement of parts hereinafter described and claimed.

Figure 1 of the drawing represents a fragmentary front elevation of the Ford motor,

Fig. 2 is a side view of same,

Fig. 3 is a longitudinal sectional view of the invention,

Fig. 4 is a perspective view of the same,

Fig. 5 is a vertical sectional view of the present Ford timer casing fitting into a recess on the engine,

Fig. 6 is a cross section through the gear casing of the invention, showing the movable cover, and

Fig. 7 is a perspective view of the cover alone.

Referring to Fig. 1 of the drawings, A represents a Ford four cylinder motor or engine, B is a circular cover fastened by means of bolts C to the housing of the engine forming the outer wall of a chamber surrounding the cam shaft (not shown in drawings) into which lubricating oil for the crank casing is injected by means of the oil inlet E. In the center of the cover B

(Fig. 5) is a recess 2' wherein the regular present Ford timer casing F fits. 65

G is the crank or driving shaft of the motor and H is a stub shaft, the pulleys I and J being mounted thereon respectively, the two pulleys being engaged by an endless belt L whereby the fan K carried by the shaft H is driven.

Between the belt L and the cover B as indicated in Fig. 2, there is a comparatively narrow space through which applicant's device is projected, the importance of which 65 will hereinafter be pointed out.

Referring to Fig. 3 of the drawings, 1 represents the cylindrical wall of the gear casing of applicant's invention and 2 the cover thereof. The cover 2 removably fits 70 as by means of recessed joint 3 over the casing 1 (the cover being conical in shape, somewhat similar to the regular Ford timer casing (Fig. 5)), so as to be held in position at its apex by the spring arms 4 and M secured on the engine by means of the bolts C. 75

The lower edge of the casing 1 is adapted to fit into the recess 2' at present on Ford engines necessitating no change to attach applicant's device. 80

A hub 6 axially tangentially arranged on the periphery of the casing and integral therewith and holding journaled the timer shaft 7, has counter-bore 8 in its outer end to rotatably hold journaled the lower end 85 of the tubular member 9 which is formed at its upper outer end with the circular transverse plate 10 having a flanged edge 10'.

The shaft 7 rotatably incased in the tubular member 9 extends beyond the flanged plate 10 thereof and carries securely on said extended part a transverse timer arm 11 carrying a spring pressed carbon contact point 12 at its outer end. 95

A cup 13 fits with its rim into the recess formed by the flange on plate 10, said cup being made of insulating material, such as fiber or rubber, and carrying the terminal posts 14 in its outer face, said posts projecting therethrough and forming contact points over which the carbon 12 rides to close the electric circuit to produce a spark when the shaft 7 is actuated. 100

From the posts 14 the wires are led to 105 and supported on the tie rod N which leads

from the radiator O rearwardly to the dashboard of the car (not shown) the wires being suitably distributed from this location. Thus the shaft 7 and the tubular member 5 may be termed extension members.

Working in the gear casing 1 are a pair of internmeshing helical gears 15 and 16 adapted to transmit motion from one shaft to another, the shafts being disposed at 10 right angles to each other, the gear 15 being firmly mounted on the lower end of the timer shaft 7 and the gear 16 firmly mounted on the cam shaft D of the engine.

It will be noted that the casing 1 is comparatively narrow when the cover is removed, so that the device may be inserted from the right hand side of the motor leftward (with reference to Fig. 1) between the belt L and the cover B and into the recess 2' in the latter without removing said belt.

Projecting upwardly and outwardly away from the cam shaft D, any suitable timer mechanism at the outer end of the extension members 7 and 9 may be firmly held in working position by a link 17 rotatably holding the tubular member 9 at a point between its ends and adapted at its upper end to be bolted in position by means of the 25 regular bolts P of the water conduit of the engine.

Thus the tubular member 9 incasing the shaft 7 is rotatably held in an oblique position, the shaft 7 being driven from one side 35 of the crank shaft and crossing the latter, actuating the arm of the timer on the opposite side thereof. A lever arm 18 having set-screw adjustment on the tubular casing 9 has pivotal connection with rod 19 at its outer end.

The rod 19 is operatively connected with the control rod on the steering post Q of the motor car whereby when the control rod is operated the timer element on the end of 45 the tubular member 9 may be oscillated to change its position relative to that of the timer arm on the shaft 7. Thus the spark may be advanced or retarded as desired.

Referring back to the gears 15 and 16, 50 (Fig. 3) 20 represents on the flat ends of the teeth of the gears, indicating marks, each of said gears bearing such marks on certain teeth whereby their position relative to each other is indicated.

The gear 16 as hereinbefore stated is rigidly mounted on the cam shaft D and in the process of attaching applicant's device, it would be very difficult to cause the marked teeth to mesh as desired, unless provision 60 were made whereby the gears may be seen through the narrow space between the radiator O and the gear casing 1.

The removable cover 2 is provided for this purpose to make it possible to see the 65 gears from the side of the machine so that

the marks 20 may be brought into proper relationship when attaching the device to the engine. This feature is very important because if it were not so provided it would be necessary to remove the entire radiator 70 involving the breaking of the water connection at the top of the engine.

While I have shown a specific form of timer in Fig. 3, I wish it understood that I may use the regular Ford timer in its stead 75 and that applicant does not claim any improvements in timer devices.

In the present Ford arrangement of the timer to the left of the fan mechanism and immediately adjacent the oil intake funnel 80 E, the wires leading from the timer are constantly spattered with oil and grease. The wires and the make and break mechanism at the outer end of the tubular member 9 are also subject to the intense heat 85 radiated from the feed manifold S which injures the insulation on the wires and said mechanism.

Thus with the construction disclosed, applicant's device may be attached to the 90 motor without requiring any special provision for attachment such as drilling, holes or providing bolts.

A pair of outwardly extending spring 95 clips 22 on the plate 10 are adapted to removably hold a timer element such as the cup 13, a notch 21 in the flange 10' being adapted to receive a pin on the element to insure its correct replacement when it has 150 been removed.

I claim:

1. In a device of the class described, in combination with the forward end of the cam shaft, and the bolted water connection from the radiator of a Ford engine, of a 105 casing secured on the engine over the end of the cam shaft, a pair of rotatable extension members journaled in said casing and rotatable one within the other, one of said members being operatively connected 110 with the cam shaft, means for rotating the other of said members, a contact point on the outer end of one of said members, a commutator to engage said contact point on the other of said members, and a link supported at one of its ends by said bolted water connection and loosely surrounding at its other end said extension members to hold the latter in a diagonal position, extending away from the cam shaft to the 120 opposite side of the engine.

2. In a device of the class described, the combination with the housing, and the forward end of the cam shaft of the Ford type of engine, a casing supported on the housing inclosing the end of the cam shaft, a differential journal in said casing axially at right angles to the cam shaft and offset relative to the longitudinal axis of the latter, a worm gear on the cam shaft, a com- 130

- paratively long shaft having a contact point at its outer end rotatable in one part of said journal and having a worm meshing with said gear, a commutator casing inclosing and engaging said contact point and having a slender body portion surrounding said shaft and rotatable at its inner end in the other part of said journal, a crank arm adjustably mounted on said body portion,
- 10 means for rocking the crank arm and a support in connection with the housing for rotatably supporting said body portion,
3. In a device of the class described, the combination with the housing having a circular recess, and cam shaft concentric therewith of the Ford type of engine, of a worm gear having peripheral teeth on the cam shaft, a ring fitting in said recess, and extending outwardly therefrom, a tangentially disposed boss having a differential bore on the periphery of said ring, the diameter of said boss being approximately equal to the width of the ring, a comparatively long shaft having a worm meshing with the teeth
- 20 of said gear journaled in part of said bore, said comparatively long shaft bearing at its outer end an element forming part of ignition mechanism, a tubular member telescoping over said shaft and journaled in said bore at its inner end and bearing another part of said ignition mechanism co-operating with said element to effect ignition when said shaft is turned, means for turning said tubular member, and a cover adapted to fit
- 30 over the outer edge of said ring and adapted to be removably held positioned on the ring to afford access to said gear and worm.
4. In a device of the class described, the combination with the housing having a circular recess, and the cam shaft of a Ford type of engine, of two part casing over the end of the cam shaft one part thereof being removable from the other part, said casing fitting loosely in said circular recess,
- 40 clamping means on the housing for said cover, a comparatively long shaft extending from the casing across the end of
- said housing to the opposite side thereof at right angles to the axis of rotation of the cam shaft but offset with respect to said axis, said shaft having a contact point at its outer end and journaled in said casing at its inner end, means operatively connecting said shaft and cam shaft, a tubular member rotatably supported on said shaft and journaled at its inner end in said casing and formed at its outer end with a commutator engaging said contact point when the tubular member is turned, means for turning said tubular member, and supporting means on the housing for said tubular member loosely surrounding the latter at a point between said commutator and casing for holding the device against rotary movement in said recess.
5. In a device of the class described, the combination with the housing and the cam shaft rotatable therein of the Ford type of engine, the housing having a recess concentric with the cam shaft, of a casing including a removable cover seated in said recess a pair of rotatable extension members extending at right angles to the cam shaft, rotatable one within the other and both journaled in the casing, one of said members having a contact point at its outer end and being operatively connected with the cam shaft and the other member bearing a commutator to engage when turned said contact point, means for turning said last mentioned member, a hanger detachably secured to the housing for rotatably supporting between their ends said extension members, a pair of holding arms on the housing adapted to be swung so as to extend to the center of said recess and press against said removable cover to hold it positioned for the purpose set forth.
- In testimony whereof I affix my signature in presence of two witnesses.
- WILLIAM P. GATCHELL.
